Statement

UNITED STATES PATENT OFFICE.

WILLIAM EDWARD VILLINGER, OF WILLIAMSPORT, PENNSYLVANIA, ASSIGNOR TO
UNITED STATES SALES COMPANY, OF WILLIAMSPORT, PENNSYLVANIA, A CORPO-
RATION OF DELAWARE.

VENDING-MACHINE.

1,168,349.

Specification of Letters Patent. Patented Jan. 18, 1916.

Application filed December 21, 1914, Serial No. 878,260. Renewed December 2, 1915. Serial No. 64,775.

To all whom it may concern:

Be it known that I, WILLIAM EDWARD VILLINGER, a citizen of the United States of America, residing at Williamsport, in the county of Lycoming and State of Pennsylvania, have invented certain new and useful Improvements in Vending-Machines, of which the following is a specification.

This invention relates to certain new and useful improvements in coin controlled vending apparatus.

The primary object of this invention is to provide a vending device for small articles such as chewing gum and candy which is especially adapted for use upon the backs of theater chairs and other places where a special form of such device is requisite that will occupy an exceedingly small space and will present no irregular surfaces capable of injuring the clothing of occupants of adjacent chairs.

A still further object is to provide a vending device having a neat and artistic appearance and which is operable upon the insertion of a coin to project a contained article through the top of the device and to uniformly position such articles flatly resting upon the top thereof, while all of the shiftable elements automatically return to their rest positions after each actuation leaving the device casing entirely closed and the operative mechanism completely concealed with the device ready for a succeeding purchaser.

A still further object is to provide a casing with a magazine compartment for containing a plurality of vendible articles and having a coin-slot for operatively positioning a coin whereby the coin forms a wedging abutment between the operating lever of the dispensing mechanism and a retaining lock for the said lever and allowing a release of the lock upon an actuation of the lever, such operation of the lever simultaneously affording an opening of the dispensing slot, a forcible expulsion of a single one of the contained articles and a closing of such slot in successive movements and prior to the automatic return of the operating lever to its normal rest and locked position.

With these general objects in view and others that will appear as the nature of the invention is better understood, the same consists in the novel combination and arrangement of parts hereinafter more fully de-

scribed, illustrated in the accompanying drawings and set forth in the appended claims.

In the drawings forming a part of this application and in which like-designating characters refer to corresponding parts throughout the several views, Figure 1 is a central longitudinal sectional view of the device with the elements in their normal positions. Fig. 2 is a central transverse sectional view upon line 2—2 of Fig. 1 thereof. Fig. 3 is a transverse sectional view of the device taken upon line 3—3 of Fig. 1. Fig. 4 is a transverse sectional view taken upon line 4—4 of Fig. 1. Fig. 5 is a view similar to Fig. 1, but with the mechanism positioned with the operating lever at the limit of its movement and illustrating in dotted lines one of the articles in its deposited position upon the top of the casing, and Fig. 6 is a perspective view of the device in its normal closed position.

Referring more in detail to the drawings, a casing 10 is illustrated having a coin entrance slot 11 and an article dispensing slot 12 in the top wall 13 thereof, while a hinged portion of the front plate 14 of the casing is normally secured closed by any desired form of lock device 15.

A plurality of the vendible articles 16 are positioned within a rack 17 and are in contact with each other, the rearmost article which is at a greater distance from the dispensing slot 12 is resiliently contacted by a pusher plate 18 having a centrally projecting rod 19 slidably positioned and telescoping within a tubular guide 20 rigidly secured to the inner face of the opposite end wall 21 of the casing, while a coiled projection spring 22 encircles the said guide and bears between the inner faces of the said follower plate and casing wall for forwardly feeding the said articles 16.

A closing plate 23 is slidably mounted upon the top of the rack 17 and has opposite depending flanges 24 overlying the edges of the rack while the forward portion 25 of the plate normally closes the dispensing slot 12 and has its forward edge seated within a receiving groove 26 in the inner side of the adjacent casing wall or end 27. Opposite depending ears 28 are provided at the rear end of the plate 23 and have a pin 29 connecting the same which is slidably engaged between the bifurcations 30 of the free end

of a substantially right-angular lever arm 31, the opposite free end of which arm is pivoted as at 32 to the casing. A curved leaf spring 33 has one end thereof secured to the casing as at 34 while its opposite end freely engages the lever arm 31 and normally maintains the said arm in the position illustrated in Fig. 1, and with the plate 23 closely positioned inwardly of the article dispensing slot.

An operating lever 35 has one end thereof 36 projecting outwardly of the casing wall 21 through a slot 37 while an operating knob or finger slide 38 is pivoted to such end as at 39 and is provided with a slide plate 40 for completely closing the said slot 37 when the operating lever is normally positioned as shown in Fig. 1. The operating lever is pivoted within the casing upon a post 41 at an angular portion of the lever, while at an opposite angle thereof a shoulder 42 is provided having a coin receiving shallow groove 43 provided with a roughened or serrated bottom 44.

A latch 45 is pivoted within the casing upon a post 46 and has a depending hook 47 adapted to normally engage beneath a projecting lug 48 of the operating arm for retaining the latter in its rest position. The portion 49 of the hook normally positioned beneath the lug 48 is straight or squared as herein shown for abutting engagement with the lug in the locking operation but such portion merges into the curved space 50 of the hook against which the lug engages for further swinging the latch to its released position when initially moved in that direction by the means hereinafter described.

A curved face 51 is provided upon the latch opposite the lever shoulder 42 and has a similar shallow groove 52 co-operating with the shoulder groove 43 for receiving and temporarily supporting a coin such as 53 which is fed thereinto by the curved coin chute 54 having its outer end registering with the coin entrance slot 11 of the casing heretofore set forth. A leaf spring 55 carried by the casing wall 21 engages the adjacent face of the hook 47 and normally retains the latch 45 in the position illustrated in Fig. 1 and ready for the reception of a coin from the aforementioned chute.

A pawl 56 is pivoted to the opposite side of the operating lever 35 from that upon which the lug 48 is located and the lever is connected to a removed point 57 within the casing by a return spring 58.

A link 59 is swingingly mounted upon the pivoting post 32 of the arm 31 and has an angular slot 60 slidably receiving therein a pin 61 of the extension 62 of the operating lever, while a hook 63 is pivoted at 64 to the said link and has its hooked end 65 normally engaging a projecting lug 66 upon the adjacent face of the said arm 31.

A spring 67 is secured at one end as at 68 to the casing while its other end is secured to the said hook 63 for normally holding the hook in its engagement with the said lug 66, while a projecting lug 69 carried by the said lever extension 62 engages the hook 63 for elevating the end 65 out of engagement with the lug 66 when the operating lever is at substantially the termination of its operative movement as illustrated in Fig. 5.

A pusher 70 carries a pin 71 at its inner end slidably mounted within an end slot 72 of the lever extension 62, while the pusher is slidably positioned within the guide bracket 73 of the rack 17 and has a foot 74 above which the forwardmost articles 16 is placed when normally positioned and being therebeneath is adapted for upward sliding movement for dispensing individually such end positioned article.

With the elements normally positioned as illustrated in Fig. 1, the coin 53 has been deposited through the slot 11 of the casing and having passed downwardly through the chute 54 is resting in the opposite co-operating holding grooves 43 and 52. With the coin so positioned, a downward movement of the operating lever being effected by a sliding impulse downwardly exerted upon the finger knob 38 results in a slight lowering of the outer end of the lever and the coin being retained within the shoulder groove of such lever by the serrated bottom 44 thereof, the coin is moved slightly in an arcuate path and exerts a slight swinging movement to the latch 45 which is sufficient to shift the shoulder 49 of the latch hook disengaged from the lug 48 and whereby the further downward movement of the operating lever engages its said lug 48 against the curved face 50 of the latch hook, thus further swinging the latch and releasing the coin from its seat, while the operating lever continues its movement to the position shown in Fig. 5. The pawl 56 engages within similar deep notches 75 at the ends of the toothed rack 76 which is fixed to the casing wall 21, such engagement taking place at the two extreme movements of the operating lever, while in the event of an interruption in the operating movement of such lever intermediate such extremes, the said pawl 56 will engage some of the intermediate teeth 77 of the rack and prevent a return of the operating lever prior to its having reached either extreme limit of its movement for completing the functional objects for which it is designed, the pawl freely ratcheting over such intermediate teeth and preferably having a lower stop spring 85. Such operative movement of the lever 35 results in so moving the pin 61 within the angular end portion 78 of the slot 60 results in shifting the link 59 and downwardly

110

130

moving the hook 63 which being engaged with the arm lug 66 initially retracts the dispensing slot guard plate 23. The continued movement of the operating lever then forces upwardly the pusher 70 and its foot 74 engaging beneath the forwardmost article within the rack, such article is projected through the dispensing slot 12 and a guard 79 on the upper end of the pusher preventing such article from falling outwardly off of the casing, the said article will take an arcuate path of movement over the beveled edge 80 of the casing top 13 at the inner side of the slot 12 and will assume its flatly reclining position upon the casing top as illustrated in dotted lines in Fig. 5. At the end of the operative movement of the lever 35, the lug 69 of such lever engages beneath the hook 63 and elevates the same off of the arm lug 66 which thereby permits the spring 33 to return the dispensing slot guard plate 23 across the said slot and the end of such plate will engage the pusher guard 79 until the pusher is again returned to its retracted position upon returning the operating lever to its normal rest position and at which time the latch hook 47 again engages the lever lug 48 and retains all of the elements locked against further movement until a further coin is inserted and the operating lever is again actuated.

It will be seen that after an actuation of the device, a release of the finger knob 38 allows the return spring 58 to pivotally move the operating lever to its normal position while the spring 67 normally holds the lever 63 engaging the lug 66 and the spring 33 returns the arms 31 and the slide plate 23 to their normal positions all as illustrated in Fig. 1.

It will be noted that the operating coin drops into the chamber 81 at the bottom of the casing from its seat within the grooves 43 and 52 and after the same has performed its function of connecting the operating lever with the releasing latch while access is had to such coin chamber by opening the door 14 of the casing. It will be seen that while the movement of the lug 61 within the portion 78 of the slot 60 operates in shifting the link 59 the required distance, the movement of the lug in the remaining portion 82 of the slot effects no swinging movement of the link. The article rack 17 heretofore described and the form of which is best illustrated in Fig. 3 of the drawings is secured within the casing by means of perforated lugs 83 carried thereby and connected to the casing by holdfast devices such as screws 84.

While the form of the invention herein shown and described is what is believed to be the preferred embodiment thereof, it is nevertheless to be understood that minor changes may be made without departing

from the spirit and scope of the invention as claimed.

What is claimed as new is:—

1. A device of the class described comprising in combination with a casing having a dispensing slot, an article supporting rack within said casing adjacent the said slot, a guard plate U-shaped in cross section slidably mounted upon the top of said rack and having a forward extension shiftable inwardly of the said slot, a pivoted operating arm engaging the said plate, a pusher slidably positioned in alinement with the forwardmost article in the rack and with the said slot, an operating lever pivoted within said casing and having one end extending exteriorly thereof and its opposite end in operative engagement with the said pusher, a link swingingly mounted at the pivotal point of the said arm and having an angular slot therein, and operative connections between the said link and aforementioned arm and lever.

2. A device of the class described comprising in combination with a casing having a dispensing slot, an article supporting rack within said casing adjacent the said slot, a guard plate U-shaped in cross section slidably mounted upon the top of said rack and having a forward extension shiftable inwardly of the said slot, a pivoted operating arm engaging the said plate, a pusher slidably positioned in alinement with the forwardmost article in the rack and with the said slot, an operating lever pivoted within said casing and having one end extending exteriorly thereof and its opposite end in operative engagement with the said pusher, a link swingingly mounted at the pivotal point of the said arm and having an angular slot therein, and operative connections between the said link and aforementioned arm and lever.

3. A device of the class described comprising in combination with a casing having a dispensing slot, an article supporting rack within said casing adjacent the said slot, a guard plate U-shaped in cross section slidably mounted upon the top of said rack and having a forward extension shiftable inwardly of the said slot, a pivoted operating arm engaging the said plate, a pusher slidably positioned in alinement with the forwardmost article in the rack and with the said slot, an operating lever pivoted within said casing and having one end extending exteriorly thereof and its opposite end in operative engagement with the said pusher, a link swingingly mounted at the pivotal point of the said arm and having an angular slot therein, and operative connections between the said link and aforementioned arm and lever.

within the disengaging line of movement of the said lever lug, a lug upon the rear portion of said lever slidably positioned within the said slot and shiftably engageable within 5 the link only during the initial operating movement of the said lever and normal positioning springs for the said hook and arm.

4. A device of the class described comprising a casing having an article dispensing slot having one lateral wall vertical and the other lateral wall inclined upwardly and away from the first wall, an article supporting rack positioned inwardly of said slot, a pusher slidably positioned in alinement 10 with the forwardmost article in the rack and with the said slot, the said pusher having a foot positioned beneath the said forwardmost article, a projecting article contacting plate carried by the said pusher adjacent its said foot and positioned on the opposite side of the dispensed article from the curved edge of the slot when the pusher is projected.

5. A device of the class described comprising a casing having a transverse slot adjacent one end of the top wall thereof, a supporting rack for articles arranged within said casing, an article engaged pusher 25 slidably positioned inwardly of the said slot and having a side plate extension flatly engaging the adjacent end of the casing and projectable through the said slot, one lateral wall of the slot being vertical and the other lateral wall being inclined upwardly and 30 away from the first wall, whereby the dispensed article is permitted to drop into flat engagement with the casing top.

35 6. A device of the class described com-

prising a casing having a dispensing slot adjacent one end of the top wall thereof, 40 said slot having the side nearest the end of said top wall forming a continuation of the inner side of the end wall, the slot further having its opposite side inclined upwardly and away from the first side, and an expelling mechanism including a plate fitting against the end wall of the casing and projectable through the slot, and the shoulder on the plate positioned intermediate its ends and arranged to engage and expel the 45 articles.

7. A device of the class described comprising a casing having a dispensing slot adjacent one end of the top wall thereof, 50 said slot having the side nearest the end of said top wall forming a continuation of the inner side of the end wall, the slot further having its opposite side inclined upwardly and away from the first side, an expelling mechanism including a plate fitting against the end wall of the casing and projectionable 55 through the slot and the shoulder on the plate positioned intermediate its ends and arranged to engage and expel the articles, 60 a supporting rack for articles arranged within the casing and a cut-off guard for said slot including a U-shaped plate carried by said supporting rack and having its lugs 65 engaging between the side walls of the casing and said rack.

In testimony whereof I affix my signature in presence of two witnesses.

WILLIAM EDWARD VILLINGER.
